UNITED STATES PATENT OFFICE.

EDWARD BIGNELL, OF LINCOLN, NEBRASKA.

APPARATUS FOR RIVER CONTROL.

Application filed February 16, 1925. Serial No. 9,543.

This invention relates to a method of and an apparatus for river control.

The primary object of the invention is to increase the scour of the natural waters of the stream against the soil to loosen it and carry it away by attrition, this being effective to enlarge channels, remove sand bars and deepen streams.

It is well known that by decreasing the velocity of the flow of streams, sand, silt, and other soil carried by the streams in suspension will be deposited by precipitation so that sand bars are built up on the bed of the streams and revetments are sometimes formed by this method, and it is also known that swift running streams carry along the sand, silt and other soil and where the velocity is sufficient the streams cut their own channels. So my invention contemplates the method, as well as an apparatus, for increasing the normal flow of streams at local points so that the increased velocity of the waters directed against the soil will agitate the soil, pick up the particles and carry them along in suspension so that the soil will be removed. In this way channels can be widened or deepened; sand bars can be undermined and removed by natural hydraulic process requiring no mechanism other than flow direction members which deflect the waters downwardly against the soil at increased velocity to increase the scour beyond that which would exist during the normal flow of the waters.

I have shown one embodiment of an apparatus for carrying out the invention and this will be specifically described herein-after, reference being had to the accompanying drawings, in which—

Fig. 1 is a plan view of a stream, a sand bar and an apparatus in position to carry out the invention.

Fig. 2 is a vertical, longitudinal, sectional view through the stream.

Fig. 3 is a cross sectional view through the stream, and

Fig. 4 is a detailed, perspective view of one of the flow directional members.

The stream 1 is shown as having a sand bar 2 located therein. Submerged in the bed 3 of the stream below the line of scour is a pile 4 to which is fastened a cable 5. The cable may settle into the bed of the stream and it constitutes a retainer or anchorage for a plurality of substantially

aligning flow directional members 6. Each member is shown as comprising a flat, buoyant or floatable body with an upstanding front end 7 to direct the waters of the stream downwardly against the soil. Each member is anchored to the cable 5 by flexible connections 8 and 9 in such a manner that the directional members will float slightly above the bed of the stream, about four inches, so that the waters coming from up-stream will strike the baffle or end 7 and be directed downwardly against the soil agitating it and loosening it by attrition. When the waters strike the baffle 7 they will tend to pile up so that ripples or eddy currents will be formed and as the waters tend to relieve the pressure against the baffles the velocity of the stream under the members 6 will be increased thereby increasing the scour and carrying away the soil.

Some sand and silt may tend to accumulate upon the members 6 so I have provided the members 6 with perforations or openings 10 and I recommend similar openings 11 in the baffles 7 so that some of the water may pass through the perforations 11 and clear off accumulations from the members 6.

It is not desirable to have the cable 5 submerged too deeply in the soil so I recommend providing a float 12 near the head of the cable, the float 12 being connected to the cable by a flexible connection 13. The number of floats used may depend upon circumstances, although ordinarily one of sufficient proportion will be adequate.

The length of the cable will be whatever is desired. For example, it may extend about a mile down the stream and it may have the requisite number of members 6 anchored to it. The down stream end of the cable may pass under a pulley 14 attached by a flexible connection to a pile submerged in the soil so that the down stream end 15 of the cable may pass under the pulley and be fastened around a pile 16, and it will be observed that the pulley 14 and the pile 16 constitute a slack take up for the down stream end of the cable 5. The purpose of employing the pulley is to provide a convenient means for hauling in the down stream end of the cable to approach a straight line passing through the pile 4 as the removal of the soil continues so as to progressively deepen the channel beyond the normal depth, or to progressively remove the sand bar 2, it being observed

from the illustration that as the sand bar 2 is cut away the members 6 should be moved closer to the shore line, that is further away from the opposite side of the stream until 5 the cable assumes substantially a straight, longitudinal line, then if desired or necessary the pile 4 or another pile may be driven at a point further inward until the sand bar is entirely removed.

10 While I recommend that the construction of the flow directional members 6 be flat and that they may be maintained in substantial horizontal positions as shown, I do not wish to be limited to the particular form of flow 15 member illustrated in Fig. 4 because other forms may be employed. For example, in some cases I may make rafts of brush and trees and submerge them slightly above the bed of the stream. Other forms may suggest 20 themselves, but ordinarily I recommend the form illustrated in the accompanying drawings.

From the foregoing it will be apparent 25 that by the method described, that is by increasing the velocity of the normal flow of that portion of the stream contacting with the soil to be removed to carry it away by the stream, the channels may be widened or deepened or sand bars removed by the 30 natural waters of the stream without any expense other than the installation of the

apparatus designed for carrying out the method.

What I claim and desire to secure by Letters-Patent is:—

35 1. An apparatus for removing soil from streams, comprising a cable, means for anchoring the up-stream end of the cable, a slack take up at the down stream end of the cable, and means carried by the cable and 40 free to follow the movable portions of the cable to cause natural waters of the stream to be deflected downward to agitate the soil and carry it away with the flowing stream.

2. An apparatus of the character described, comprising a cable anchored to lie lengthwise in a stream, and a buoyant, flat body anchored to intermediate portions of the cable and having a deflector extending 45 upwardly and forwardly from its up-stream 50 edge.

55 3. An apparatus of the character described, comprising a cable anchored at its ends to lie longitudinally in a stream, a plurality of directional members each comprising a flat, apertured, buoyant body, flexibly anchored to the cable and having an upwardly and forwardly inclined body at its up-stream edge, and a float attached to the 60 cable near its up-stream end.

In testimony whereof I affix my signature.

EDWARD BIGNELL.
